[57] CLAIM

The ornamental design for a combined vehicle window arm rest and detachable article holder, as shown and described.

DESCRIPTION

FIG. 1 is a top, front, perspective view of a combined vehicle window arm rest and detachable article holder showing my new design with the article holder in partially detached condition;

FIG. 2 is a bottom plan view thereof;

FIG. 3 is a rear elevation view thereof with the opposite end of the article holder in partially detached condition; and,

FIG. 4 is an end elevational view thereof rotated ninety degrees, with the article holder fully attached to the arm rest.

FIG. 1

FIG. 2

FIG. 3

FIG. 4
